United States Patent Office.

BENJAMIN D. WHEAT, OF MOUNT CARMEL, ILLINOIS.

Letters Patent No. 85,975, dated January 19, 1869.

IMPROVEMENT IN DOFFER FOR CARDING-ENGINES.

The Schedule referred to in these Letters Patent and making part of the same.

To all whom it may concern:

Be it known that I, BENJAMIN D. WHEAT, of Mount Carmel, in the county of Wabash, and State of Illinois, have invented a new and improved Ring-Doffer for Wool-Carding Engines; and I do hereby declare that the following is a full, clear, and exact description thereof, reference being had to the accompanying drawings, making a part of this specification, in which—

Figure 1 is a diametrical section taken through the improved ring-doffer.

Figure 2 is a view of the expanding cones and doffer-shaft detached from the cylinder of the doffer.

Figure 3 is a cross-section through the doffer-cylinder, taken in the plane indicated by line $z z$ in fig. 1.

Similar letters of reference indicate corresponding parts in the several figures.

This invention relates to an improvement on the construction of the cylinders of ring-doffers, and is designed to so construct them that they can be expanded or contracted diametrically for the purpose of readily removing or applying the doffing-rings or bands, and also for allowing such rings or bands to be tightened after they are adjusted in proper places upon the cylinders, as will be hereinafter explained.

To enable others skilled in the art to understand my invention, I will describe its construction and operation.

The drawing represents a very short doffing-cylinder, containing but three rings or bands, but in practice this cylinder may be made of the usual length.

The cylinder proper consists of two or more longitudinal sections or segments A A, which are preferably made hollow and of cast-iron, with internal partitions that serve to strengthen the sections or segments.

These segments A, which constitute the cylinder, have their edges $a a$, lying nearest the shaft B, inclined from the middle of the length of these sections or segments to the ends thereof, as shown in fig. 1.

When these segments are all put together around the central shaft B, as shown in fig. 3, spaces will be left for receiving two circular wedges, C C, which are applied loosely upon the shaft B, so that they can be moved in a direction with the length thereof.

These wedges are constructed with oblong slots $b b$ through them, through which rods D D are passed, which rods also pass through the shaft B and cylinder-segments or sections A A, as clearly shown in figs. 1 and 3.

The ends of these rods have nuts and heads upon them, to keep them in their places, which nuts and heads are in recesses, $c c$, made in the segments or sections A, so as not to extend beyond the circumference of the cylinder.

The rods D serve to prevent the segments A becoming detached from the shaft B and cones C, when the rings or bands are removed from the cylinder, and these rods also serve to prevent the segments from turning around the shaft B.

The central shaft B has screw-threads cut upon it for receiving nuts $d d$, by means of which the cones or circular wedges C C can be forcibly moved toward each other, and the segments thereby expanded so as to increase the diameter of the cylinder or drum. By turning back the nuts $d d$, and drawing out the cones or circular wedges C C, the segments constituting the cylinder or drum can be moved nearer to the axis of shaft B, and this cylinder or drum thus reduced in diameter.

I surround the circumference of the drum with thin sheet-metal strips $g g$, or rings of other substance, leaving their ends lapping but not united together. These strips or rings will serve as coverings for the spaces left between the segments A A, and allow them to be expanded and contracted, as above described.

Surrounding the covering g , are the doffing-rings or bands G G, which may be constructed in the usual well-known manner.

It will be seen from the above description that my improved doffing-cylinder or drum can be expanded or contracted in diameter by simply adjusting the circular wedges, and that the rings or bands G G can be readily applied upon or removed from this cylinder or drum, and made as tight thereupon as may be required, which operation of tightening is performed by setting up the nuts and cones after the rings or bands have been properly adjusted in their places.

Having described one practical mode of carrying out my invention,

What I claim as new, and desire to secure by Letters Patent, is—

1. A segmental ring-doffing cylinder or drum, which is made expandible by means of sliding cones, governed by nuts and screws on the central shaft, substantially as described.

2. An expandible doffing-cylinder or drum, the segments of which are attached, by rods D, to a central shaft B, substantially as described.

3. The application of one or more expandible covering-pieces g to an expandible ring-doffer, constructed substantially as described.

BENJAMIN D. WHEAT.
